(57) **CLAIM**

The ornamental design for a mitt for a wheelchair user, as shown and described.

DESCRIPTION

FIG. 1 is a top perspective view showing my new design for a mitt for a wheelchair user, in an unworn, opened state; FIG. 2 is a top view of the mitt thereof, when worn on a user's hand; and,

FIG. 3 is a bottom view of the mitt thereof, when worn on a user's hand.

The short dashed broken line portions that form each oval in the pattern of ovals and the user's hands form no part of the claimed design. The long dashed broken line portion represents stitching that forms part of the claimed design.
